UNITED STATES PATENT OFFICE.

LOUIS HORNBERGER, OF MERIDEN, CONNECTICUT, ASSIGNOR TO THE
EDWARD MILLER & COMPANY, OF SAME PLACE.

DESIGN FOR A LAMP-BURNER.

SPECIFICATION forming part of Design No. 23,722, dated October 23, 1894.

Application filed September 19, 1894. Serial No. 523,500. Term of patent 14 years.

To all whom it may concern:

Be it known that I, LOUIS HORNBERGER, of Meriden, in the county of New Haven and State of Connecticut, have invented a new 5 Design for Lamp-Burners; and I do hereby declare the following, when taken in connection with the accompanying drawing and the letters of reference marked thereon, to be a full, clear, and exact description of the same, 10 and which said drawing constitutes part of this specification, and represents, in the figure, a view in front elevation of a lamp-burner embodying my design.

My invention relates to a design for lamp- 15 burners, and consists in the configuration and ornamentation as hereinafter described and shown in the accompanying illustration.

My newly designed lamp-burner has an embossed, pierced band A interposed between the burner-gallery B and the burner-collar C, 20 which may be of any shape and ornamentation, the essential feature of my design being an embossed, pierced band, located between the gallery and the collar of a lamp-burner. 25

I claim—

The design for a lamp burner, substantially as shown and described.

In testimony whereof I have signed this specification in the presence of two subscribing witnesses.

LOUIS HORNBERGER.
